UNITED STATES PATENT OFFICE

2,141,762

VENTILATOR

Leo I. Ravven, Boston, Mass., assignor to Air-O-Matic Ventilator Company, Roxbury, Mass.

Application March 6, 1936, Serial No. 67,518

1 Claim. (Cl. 230—134)

The present invention relates to a means for aiding ventilation, and may be applied to openings from the exposed atmosphere to a building or in any position where a window, door, transom or opening may exist.

The present invention is particularly useful in producing a diffused flow of air from the outside into a heated room and in such a manner that very little or no draft will be felt, and that rain or snow will be excluded.

The present invention is particularly applicable as an insertion in an open window or an open door, and in the present application particularly, may be applied to different types and sizes of windows and be inserted either permanently or removable wherever it is necessary or desirable.

The advantages of the present invention will be more fully understood and appreciated by a consideration of the embodiment described in the specification below and taken in connection with the drawings.

In the drawings, Figure 1 shows a front elevation of a window with the invention in place.

Figure 2 shows an enlarged view of the center rotating element indicated in Figure 1.

Figure 3 shows a sectional view taken through the center of Figure 2, on the line 3—3.

Figure 4 shows a face view of a detail.

Figure 5 shows a section on the line 5—5 of Figure 4.

Figure 6 shows a vertical view of a modification indicated in Figure 1.

Figure 7 shows a still further modification of a detail.

Figure 8 shows a detail of an element indicated in Figure 7.

Figure 9 shows the detail indicated in Figure 8 from a side view.

Figure 10 shows an enlarged section of the center of the rotating unit shown in Figures 2 and 3, and,

Figure 11 shows a further detail of a modification.

The invention may be inserted in the lower part of the window as shown in Figure 1 beneath the lower glass frame when in a raised position. It comprises a wall or plate member 1 which may be of glass and transparent, translucent, or opaque and of any suitable material. The plate member 1 may be surrounded by frame elements 2, 3, 4 and 5. The elements 3 and 4 may be made to extend outward to the sides of the window frames 6 and 7 so as to fill up the entire space at the sides of the device when the window is opened. The entire frame may be made in a length longer

than necessary for the ordinary windows, and it may be cut to size by cutting or trimming off one or more of the side pieces 8, 8, which may be made as one piece and grooved by grooves 9, 9, so that the pieces 8, 8, may easily be severed from the frame. At the center of the plate or wall 1, there is provided a perforation in which may be inserted the assembly 10 containing the rotating element as will presently be described.

The unit 10 comprises a frame made of two pieces 11 and 12 which are cylindrical in shape with an outwardly extending flange 13, 13, and an inwardly extending flange 14 and 15, the flanges 14 and 15 actually forming an outwardly facing flat ring parallel with the surface of the wall or plate 1. The unit is set into the wall by clamping the wall between the outwardly extending flanges 13, 13, by means of the nuts and bolts 16, 16, or by riveting or in any other suitable manner. Across the outer faces 14 and 15, there is mounted a flat bar 17, 17, passing through the center of the opening. The rotor within the unit is pivoted in this bar. This rotor 18 is formed of a flat molded Celluloid piece having radially extending bars 19 extending from a center hub 20 and joining in an outer ring 21. These bars 19 support the outwardly extending flaps or vanes 22 which are pressed from the flat Celluloid piece leaving perforations or openings between the bars 19, 19. The hub 20 and the rest of the elements just described are shaped from a single piece of Celluloid, the center hub being coned or hemispherically shaped as indicated by 23 particularly in Figure 10 and is formed to grip the shaft 24, the ends 25 and 26 of which are mounted in the bars 17, 17.

On the other side of the Celluloid rotor at the center is another cap or cone 27, preferably made of metal and substantially the same size as the Celluloid center hub. This cap is provided with a flat flange 28 abutting the Celluloid surface and is held fast to it by means of the clamping fingers 29 which pass through the Celluloid rotor at the vane openings. As many of these fingers may be formed on the cone 27 as is necessary to obtain a good support. The shaft 24 may be cemented into the cone 27 so that the shaft will move with the cone.

As indicated in Figure 2 there is provided an outer Celluloid ring 21 extending well within the frame formed by the pieces 11 and 12. The vanes 22 may be extended inwardly or outwardly but are preferably extended inwardly or away from the direction of the draft, so that in Figure 1, assuming the device is viewed from the inside

towards which the air is flowing, the rotation of the vanes will be clockwise.

The rotor is preferably made of Celluloid and the rest of the parts of aluminum, with the exception of the shaft element, which I have found suitable to make of wood, such as lignum vitae. In this manner the device is not only impervious to moisture and will not rust, but is extremely light, and lends to a low cost of manufacture.

- 10 As indicated in Figures 4 and 5 I may employ a front cover 30 which may be pivoted to the frame piece 14 by means of a pivot 31. The cover may also be provided with a handle 32 so that it may easily be opened or closed. This cover may be arranged as indicated in the modification shown in Figure 6 wherein a cord 33 is provided attached to the handle 32 and having at one end a ring 34 to provide a simple grip for the finger. The cord 33 is preferably wrapped or tied around 20 the handle 32 and passed upward through an eye 35 in the frame and then over to another eye 36 on the other side of the ventilator, and then allowed to hang downward as indicated by the end 37 with the ring 38 attached thereto.
- 25 In the modification shown in Figure 6, the end elements 39, 39 are detachable from the frame to which they are nested by means of locking elements 40 which project from one side of the end strips 39 into a corresponding position in the next 30 end strip. In each case a final finishing strip is provided as indicated at 41. The arrangement shown in Figures 1 and 6 may also be permanently applied to the window. This is accomplished by the use of a set fixture shown in Figures 8 and 9 and shown as applied in Figure 7. The side fixture 42 is a board or bar that is grooved on the outside edge and prepared to receive the entire frame. This end piece 42 is provided with a groove 43 by the extending side walls 44, 44, and the piece itself may be held to the frame with a single screw 45 in such a manner as to act as a pivot and allow the frame to be applied in an inclined fashion against the lower cross piece of the window itself.
- 45 In place of building the frame with side extensions as shown in Figures 1 and 6, an extensible end piece as indicated in Figure 11 may be used. This piece 46 is bent over on itself at the edge to form a slideway for the frame as indicated at 47, while at the opposite side there is provided a pivoted slideway 48 pivoted to the end piece 46 by means of the pivot 49. The outer end of the piece

46 may be bent over at an angle as indicated by 50 to fit against the frame when the end piece is in at its greatest distance. The pivoted slideway at one edge is provided to allow the end to be easily adjusted.

5 In order to secure a perfect balance of the rotor element, the hub space previously described may be filled with a plastic substance 51 as putty for instance, or with a lubricant as grease or Vaseline, and be provided with similar shots as 52 to 10 properly weight and balance the rotor element. If desirable, there may also be provided in the frame element as indicated in Figure 2, a clutch or stop piece 53 pivoted to the frame at 54. This stop piece is used in its upright position to prevent the rotor from going around and when thrown to the right from the position in Figure 2, allows the rotor to turn freely about.

15 The invention when installed in a window or the like will operate on a very small difference in pressure, since the rotor is constructed of such light material. The cylinders 11 and 12 may be provided with drain holes 60 to effect drain of water that may settle from rain or the like when installed.

20 When operating, the vanes being inclined outwardly at a substantial angle, will diffuse the air for a considerable area and greatly facilitate a constant and uniform flow.

25 The device may be allowed to remain permanently in the window frame or may be removed. If allowed to remain permanently in the window frame the air flow may be regulated not only by the stop element 53 but also by means of the cover 30 which may be opened as much as desired.

30 Having now described my invention, I claim:—
35 In a ventilating device of the type described, a Celluloid rotor comprising a flat disc having vanes formed of radial sectors inclined at an angle to the plane of the disc and a center hub bearing element formed with one convex face constituting an integral part of said Celluloid disc, a convex member opposite said convex face having clamping fingers at the edges thereof clamping over the vanes at their inner vertices said hub elements forming an enclosed space having a field therein of plastic material and a weight element at one side thereof and shaft means positioned centrally in said hub and held rigidly in place by said plastic means.

40 LEO I. RAVVEN. 50
